FRITZ TRACHSEL, OF BERN, SWITZERLAND, ASSIGNOR TO CHR. GFEILLER AKTIEN-
GESELLSCHAFT, OF BERN-BUMPLIZ, SWITZERLAND.

SWITCH DEVICE FOR AUTOMATIC TELEPHONE-EXCHANGE SYSTEMS.

Application filed April 14, 1927, Serial No. 183,764, and in Germany April 17, 1926.

The present invention relates to a switch device in an automatic telephone exchange system provided with a selecting device arranged after a two coordinate system. In 5 this system each subscriber has his subscriber's set, with contrivances, which by means of an electro-magnet are brought into a position of readiness so that they may be seized and displaced by a switch member for 10 the purpose of closing contacts.

In the switch devices heretofore known the mentioned contrivances did not participate electrically in bridging the subscribers. Generally springs were employed operating 15 quite mechanically and transmitting the movement on contact springs. According to the present invention said springs are electrical conductors which are making contact with the switch member which is likewise 20 an electrical conductor.

The annexed drawing represents as far as it is necessary an automatic telephone exchange system having the above-mentioned features.

25 Fig. 1 is a perspective view of the principal parts of a subscriber's set of said system and

30 Figs. 2, 3 and 4 show details of these parts and a switch member cooperating with the same;

Fig. 5 is an inverted perspective view showing certain details of the sliding rods mentioned herein;

Fig. 6 is a further view of the same purpose and

Fig. 7 is a diagram of the electrical connections.

All parts of the subscriber's set are mounted on a stirrup-shaped bracket B provided 40 with bent-off fastening lugs L. The subscriber's magnet M is located alongside of the left-hand leg of said bracket and its rectangularly bent armature An is pivotally held at the outer edge of an intermediate 45 bracket leg T fixed to the bracket B. This additional bracket leg carries also the contact set p which is held insulated and is controlled by the movements of the armature so as to cause the contact of two blades of said 50 set whenever the armature is attracted.

Small angular brackets k are riveted into cut-outs of the stirrup-bracket and insulated flat-springs du are fastened thereto. These 55 springs are directly connected by wires e¹, e² to the bridging-relay set, as shown in the

copending application 101,516 filed April 12, 1926. They are leaning sideways against the insulated carrier pins M¹, M² mounted on the hollow rods Zu¹, Zu² and are extended into the reach of the blades St representing 60 the switch member. The rod Zu¹ is hinged at one end to the armature An and slidingly held at its other end in the right hand leg of the stirrup-bracket. The rod Zu² is 65 slidingly held at its hollow left-hand end on a pin g fast to the bracket-leg T and at its other end in the right-hand leg of the bracket B. When the armature is attracted it moves the rod Zu¹ against the effect of the contact springs du and this movement brings 70 the springs du into the reach of the already mentioned blades St which represent here the second switch members, as shown in the copending application 101,516. The blades St are intended to displace the contacts, they 75 are constituted of a plurality of insulated lamellas kept together by means of cross bolts Q.

As represented in Figures 3 and 4 the 80 blades are provided with sideways bent ears N. These ears are staggered and will seize the bridging contacts du at the beginning of the upward movement of the blades either at once when the subscriber of the respective set is calling or only then when the blade 85 has moved upwards after several effected switch movements and when the desired subscriber has to be switched out. Thus the bridging contacts are seized here directly by the blades and are displaced while these 90 blades are continuing their movement. This movement will cause a displacement of the rod Zu² by means of the carrier pins M² and the displacement will allow to operate the contact set W by means of the dog Au². 95 By means of this contact set the circuit of the subscriber's magnet appertaining to the contacting set will be broken and thereby the armature as well as the rod Zu¹ will again retake their initial position. 100

According to Figures 5 and 6 the sliding rods Zu¹ and Zu² are mounted between one of the two legs of the stirrup-shaped bracket B and an intermediate leg T is riveted to 105 said bracket. To the end of this intermediate leg the angular armature An is pivotally attached by means of the two screws a and one end of the sliding rod Zu¹ is connected to the end of the angular armature at b so that when it is moved by the 110

rocking armature it will always maintain its parallelism with the rod Zu^2 (Fig. 6). Said armature carries a knob c which when the armature gets attracted will push one blade 5 of the contact set p against the other blade so that the contact is established at d between the two blades (Fig. 6).

The end of the other sliding rod Zu^2 which is hollow is sleeved over a pin e fixed to 10 the leg T inside of a cut-out of the armature. It is slidingly guided thereby while its other end after crossing the leg of the bracket B carries the insulated dog Au^2 adapted to control the contact set w .

15 What I claim as new is:

In an automatic telephone exchange system the combination of a switch device comprising a stirrup-shaped bracket, an electromagnet fixed to one leg of said bracket, a 20 contact set fixed to the outside of the other leg and included in the circuit of the magnet, an intermediate leg of the bracket and an angular armature pivoted at the end of this leg, two rods disposed inside of the bracket

and provided with insulated carrier pins, 25 one rod slidingly held at one end in a bracket leg and attached to said armature and the other rod slidingly supported in a leg of the bracket and in the intermediate leg and attached to a contact member of said contact set, transverse insulated contact springs, capable of maintaining the relief position of said armature while leaning against the pins of the first rod and capable of assuming a position of readiness when displaced by the first rod hinged to the armature, and electrically conducting switching blades arranged transversely to said rods, and springs near the ends of the latter and 30 provided with sideways projecting lugs adapted to seize the ends of these springs in order to establish the contact and to displace the second rod for breaking the circuit of the magnet and restoring again the initial 35 position.

In testimony whereof I affix my signature.

FRITZ TRACHSEL.
